UNITED STATES PATENT OFFICE.

FRANK CONRAD, OF PITTSBURGH, PENNSYLVANIA, ASSIGNOR TO WESTINGHOUSE ELECTRIC & MANUFACTURING COMPANY, A CORPORATION OF PENNSYLVANIA.

RADIO TRANSMITTING SYSTEM.

Application filed December 23, 1924. Serial No. 757,581.

My invention relates to radio signalling systems, and particularly to a construction for a power connection between an oscillation radiator and an oscillation generator.

5 An object of my invention is to provide a radio signalling device for controlling the degree of coupling between an oscillation generator and an oscillation radiator.

Another object of my invention is to provide 10 a connecting device that is adapted to prevent the transfer of oscillatory energy at frequencies higher than the fundamental frequency.

Another object of my invention is to provide 15 means for reducing the current value required to transmit a given amount of energy from an oscillation generator to an oscillation radiator.

In the prior construction of radio sending apparatus, it has been common to construct 20 an oscillation radiator comprising an antenna and a counterpoise with a connection therebetween, in which may be provided a coiled inductance. It has also been customary 25 to construct an oscillation generator in which triodes and suitably connected inductances, capacitances and power sources cause the development of radio frequency oscillations. It has been customary further 30 to position the coiled inductance, in the circuit connecting the antenna and counterpoise, in inductive relation to the inductance comprising a portion of the oscillation generator, thus obtaining a transfer of energy 35 therebetween by means of magnetic coupling. This construction has been found objectionable because of the necessity either of bringing a portion of the radiator circuit within the building housing the oscillation generator, or of mounting the inductance of 40 the oscillation generator at a position without the housing structure in order to obtain the necessary magnetic coupling.

In my previously filed application, Serial 45 No. 666,703, filed Oct. 5, 1924, and assigned to the Westinghouse Electric and Manufacturing Company, I disclose a construction for a radio sending apparatus in which an antenna and counterpoise are provided, connected by an inductance and energized by an oscillation generator of the usual type, connection therebetween being made by a conductor and an interposed variable condenser. The present construction containing 50 the capacitive connection has been found

to offer important advantages over other types which advantages are listed in that disclosure.

None of the previously utilized radio sending systems, however, provide satisfactory 60 stopping means for preventing the transfer of oscillation harmonics higher than the fundamental oscillation frequency to the antenna, and radiation therefrom.

My invention provides a construction in 65 which an inductance is substituted for the capacitance in the connecting conductor of the system of my previously mentioned disclosure. It is known that the impedance of a condenser varies inversely as the frequency, and that the impedance of an inductance varies directly as the frequency. Because of this fact, the inductance, when adjusted to interpose the same impedance to the fundamental frequency of oscillation as 70 would be interposed by a condenser similarly placed, interposes a much higher impedance to the higher harmonic frequencies.

By reason of this characteristic, a much purer frequency is supplied to, and radiated 75 from, the open oscillating system.

Other objects and structural details of my invention will be apparent from the following description when read in connection with the accompanying drawing, wherein:

85 The single figure is a diagrammatic representation of an embodiment of my invention.

In the drawing, an aerial 1 and counterpoise 2 are connected by a conductor 3 in which may be interposed a tuning inductance 4 and an ammeter 5. This comprises the open oscillating system. An oscillation generator 6, comprising a triode 7 and inductance 8, capacitances 9 and 11 and the usual auxiliary devices required for the proper functioning of a triode oscillator are provided. A connection is made between a point on the inductance 8 and a point upon conductor 3 other than the electrical mid-point of the radiator system by a transfer conductor 12, a portion of which comprises a coiled inductance 14.

100 In the operation of my device, the open oscillating circuit comprising the antenna 1, counterpoise 2, and the inter-connected circuit apparatus 3, 4 and 5, may be tuned to the desired frequency by adjustment of the inductance 4. Likewise, the oscillation generator 6 may be adjusted to substantially the same frequency by adjustment of the contact 110

points upon inductance 8. This adjustment may desirably be made with lead wire 12 removed therefrom. Upon the completion of these two adjustments, connection may be established between the open radiator circuit and the oscillation generator through conductor 12 and inductance 14. Inductance 14 may then be adjusted to a value which will permit of the transfer of the desired amount of energy from oscillator 6 to the open radiator circuit.

The presence of inductance 14 then permits the transfer of the only desired amount of energy to the radiating circuit at the fundamental frequency and restricts, very strongly, the transfer of energy at higher frequencies, such as the higher harmonics, thereby resulting in a very desirable purity of radiation frequency.

It has further been found that the energy transfer between the generator device and the radiation device takes place by means of alternating electric currents at substantially zero phase displacement passing through the conductor 12 and the inductance 14. Thus it is possible to make the conductor 12 and inductance 14 of much smaller size than would otherwise be required.

While I have shown only one embodiment of my invention in the accompanying drawings, it is capable of various changes and modifications therefrom without departing from the spirit thereof, and it is desired,

therefore, that only such limitations shall be placed thereon as are imposed by the prior art or indicated in the appended claims.

I claim as my invention:

1. In combination, a radiating circuit, an oscillation generator and a connection between them, the oscillation generator including a closed tuned circuit and means for maintaining oscillations therein and the connection extending from a point in said closed circuit to an intermediate point in said radiating circuit near but not at the mid-point thereof and including an inductive reactance.

2. In combination, an oscillation generator including a closed tuned circuit determining the frequency of the oscillations and a vacuum tube device cooperating with said circuit to maintain said oscillations, a radiating circuit comprising open capacitive elements and a connecting inductive element associated therewith to form an electrically oscillating system having the same frequency as said closed tuned circuit, a connection from said closed circuit to a point near a voltage node of said radiating circuit whereby the connection may be of small size and a device in said connection for preventing the transfer of energy or harmonic frequency.

In testimony whereof, I have hereunto subscribed my name this 12th day of December, 1924.

FRANK CONRAD.
